UNITED STATES PATENT OFFICE.

PAUL C. VAN ZANDT, OF CHICAGO, ILLINOIS, ASSIGNOR TO ALLIS-CHALMERS MANUFACTURING COMPANY, OF MILWAUKEE, WISCONSIN, A CORPORATION OF DELAWARE.

ROLL-CRUSHER.

1,309,827.

Specification of Letters Patent. Patented July 15, 1919.

Application filed September 20, 1915. Serial No. 52,123.

To all whom it may concern:

Be it known that I, PAUL C. VAN ZANDT, a citizen of the United States of America, residing at River Forest, Chicago, in the county of Cook and State of Illinois, have invented a certain new and useful Improvement in Roll-Crushers, of which the following is a specification.

This invention relates to improvements in the construction of crushing devices and is particularly applicable to that class of crushing devices known as roll crushers.

An object of the invention is to provide a roll crusher which is simple in construction and efficient in operation. One of the more specific objects is to provide a roll crusher of maximum capacity.

The invention consists primarily in forming at least one roll of either a single or a multiple roll crusher, with projections or knobs of different heights, the purpose of such formation of the projections being to cause large pieces of rock to be tumbled over from one end of the roll to the other, thereby preventing lodging of the rock in a set position and grooving instead of fracturing thereof by the projections. While the present disclosure shows the invention as applied to a single roll crusher, it will be apparent that the same is applicable to other types of roll crushers. The present disclosure also shows the projections arranged in regular straight rows extending longitudinally of the roll, such disclosure having been selected merely as being a simple embodiment of the invention.

Several of the novel features of single roll crushing construction which are disclosed herein, form no part of the present invention.

A clear conception of an embodiment of the invention may be had by referring to the drawing accompanying and forming a part of this specification in which like reference characters designate the same or similar parts in the various views.

Figure 1 is an end view of a crushing roll constructed in accordance with the present invention.

Fig. 2 is an elevation of the crushing roll disclosed in Fig. 1.

Fig. 3 is a transverse vertical section through one form of crusher having the present invention applied thereto, the section through the roll being taken along the line

III-III of Fig. 2 looking in the direction of the arrows.

The roll crusher, see Fig. 3, comprises a crushing roll 18, and an anvil 17 spaced therefrom to form an intermediate or direct crushing member. The crushing roll 18 is mounted upon the main roll shaft 1 which is supported in suitable bearings, not shown, in the main frame 20. The anvil 17 is supported at its upper extremity from the supporting shaft 21 which is also mounted in the main frame 20. The lower extremity of the anvil 17 engages a reaction rod 25 which is connected with a plurality of reaction springs 23 by means of suitable tension devices 24. The arrangement of the anvil 17, springs 23, and devices 24 is such that if an unduly hard piece of material enters the direct crushing chamber, the lower extremity of the anvil 17 will automatically recede from the roll 18 and will prevent the hard material from breaking the crusher elements.

The feed hopper 19 is located above the crusher elements and directs the material toward the upper portion of the roll 18 and of the intermediate crushing chamber. The crushed material is delivered from the machine at the lower extremity of the anvil 17. The roll 18 is given a rotary motion by means of power applied at the driving pulley 22. The pulley 22 is mounted upon the main driving shaft 26 which is geared or otherwise drivingly connected to the main roll shaft 1.

Referring specifically to Figs. 1 and 2, the roll 18 comprises an octagonal core 2 and a circumferential series of roll plates 3, 4, 5, forming a shell for the core 2. The roll core 2 is fixed to the main shaft 1 by means of any suitable securing device, such as a key 6. The periphery of the core 2 is provided with a series of longitudinal ribs 16 which engage similarly shaped recesses in the plates 3, 4 and 5.

The roll plates may be divided into three classes, namely, the ordinary roll plates 3, the right hand slugger plates 4, and the left hand slugger plates 5. Each of the plates 3, 4, 5, has a number of projections 15 formed thereon. The plates 3 are provided only with projections 15. The right hand slugger plates 4, in addition to having projections 15 formed thereon, are provided with slugger projections or knobs 7, 8, 9, 10. The left hand slugger plates 5, in addition to hav-

ing projections 15 formed thereon, are provided with slugger projections or knobs 11, 12, 13, 14. In order to readily define the knobs of the slugger plates, the knobs 7, 11, 5 will be designated as the lowest; the knobs 8, 12, will be designated as the second lowest; the knobs 9, 13, will be designated as the second highest; and the knobs 10, 14, will be designated as the highest. The slugger 10 knobs of the right hand plates 4 are arranged with the lowest knob 7 at the left, and the highest knob 10 at the right, as viewed in Fig. 2. The slugger knobs of the left hand plates 5 are arranged with the 15 lowest knob 11 at the right, and the highest knob 14 at the left, as viewed in Fig. 2. The second lowest knobs 8, 12, are located adjacent the lowest knobs 7, 11, respectively, while the second highest knobs 9, 13, are 20 located adjacent the highest knobs 10, 14, respectively.

During the normal operation of the crusher, the roll is rotated in an anticlockwise direction as viewed in Fig. 3, by means 25 of power applied at the pulley 22. The material to be crushed, which generally varies considerably in size, is admitted either continuously or intermittently to the feed hopper 19. The relatively small pieces of the charge pass readily through the hopper 19 and the crushing chamber formed between the anvil 17 and the roll 18, being properly reduced during their downward passage and eventually discharged from the machine. 30 The relatively large pieces of material contained in the charge will not, however, enter the direct crushing chamber and must first be broken into fragments by the sluggering action of the knobs formed on the roll 18. As the slugger knobs successively approach the large pieces of material they deliver sharp blows thereagainst and eventually break the pieces into fragments which are sufficiently small to pass into the chamber adjacent the anvil 17. 45

If the material operated upon is relatively soft or porous in its nature, the large pieces will tend to lodge in a set position at the mouth of the direct crushing chamber and 50 the roll projections will not readily break the same into smaller fragments. In order to prevent this undesirable action, the roll 18 is provided with the slugger knobs of different heights. These knobs will tend to tumble or roll the large pieces of material from one end of the roll 18 to the other and to 55

prevent lodging thereof in a set position until grooving occurs. By this means the large pieces of material are readily broken into small fragments of a size permitting passage 60 thereof into the direct crushing chamber.

It will thus be noted that the slugger knobs of different heights, due to their action in preventing lodging of the material in the mouth of the crushing chamber, greatly enhance the capacity of the crusher and effectively prevent stalling of the machine. The 65 removability of the plates 3, 4, 5, permits renewal of any one or more of these plates without necessitating removal of the others. 70 The arrangement of the knobs in straight rows extending longitudinally of the roll, also somewhat simplifies the construction of the plates and reduces the cost of construction of the machine, to a minimum. 75

It should be understood that it is not desired to be limited to the exact details of construction shown and described, for obvious modifications will occur to a person skilled in the art. 80

It is claimed and desired to secure by Letters Patent,—

1. In a crusher, a roll having an axis and a plurality of longitudinally arranged series of projections, each series comprising at least 85 three projections of successively increasing heights, and the bases of said projections being at the same distance from said axis.

2. In a crusher, a roll having a plurality of longitudinally arranged series of projections, each series comprising at least three 90 projections of different heights, and the low projections of one series being arranged circumferentially in line with higher projections of another series. 95

3. In a crusher, a roll having two longitudinally arranged series of projections, the projections of one series alternating with those of the other, one series comprising projections of different heights and the other 100 comprising projections of equal heights.

4. In a crusher, a roll having two longitudinally arranged, substantially aligned series of projections, the projections of one series alternating with those of the other, one 105 series comprising projections of successively increasing heights and the other comprising projections of equal heights.

In testimony whereof, the signature of the inventor is affixed hereto.

PAUL C. VAN ZANDT.
